UNITED STATES PATENT OFFICE.

JOHN FREDERICK W. JOST, OF PHILADELPHIA, PENNSYLVANIA.

METHOD OF BURNING OIL FROM WICKS.

No. 801,878.

Specification of Letters Patent.

Patented Oct. 17, 1905.

Application filed February 12, 1901. Serial No. 47,020.

To all whom it may concern:

Be it known that I, JOHN FREDERICK W. JOST, a citizen of the United States, residing at Philadelphia, in the county of Philadelphia and State of Pennsylvania, have invented a certain new and useful Method of Burning Oil from a Wick, of which the following is a specification.

The principal object of the present invention is to provide for the production from even kerosene-oil fed from a wick of blue or heating flames of any desired character, including those which are well adapted to heat mantles and the like to incandescence without deteriorating the wick by baking it or suffering it to receive a deposition of pyroligneous products; and to this and other ends herein-after set forth the invention stated in general terms comprises the establishment of conditions adverse to combustion between the wick and the base of the flame; and the invention further comprises the method of burning oil from a wick which consists in maintaining an interspace between the flame and the wick by feeding unbalanced supplies of finely-divided air between the wick and flame either with or without the addition of further supplies of air between the wick and flame; and the invention further comprises the improvements hereininafter described and claimed.

Of course the invention can be practiced by a variety of means or instrumentalities. However, for the sake of clearness of explanation I have illustrated in the accompanying drawings diagrammatic views, principally in central section, showing the invention.

In the accompanying drawings, *a* is the wick, and the flame may be either unitary or subdivided, and it is designated as *b b'*. However, in any event there is between the wick and the flame or the lowest portion of it an interspace *c*. This interspace comprises a region of conditions adverse to combustion. Through this interspace *c* vapors travel from the wick to the flame; but the flame may not by reason of this space bake or otherwise deleteriously affect the wick. Into this interspace *c* are introduced unbalanced supplies of finely-divided air, and these supplies not only insure the existence of the interspace, but also establish conditions adverse to combustion and also prevent deposition of carbon and pyroligneous products on the wick, and since these supplies of air may proceed from what beneath the top of the wick they cause the carbon and pyroligneous products to oxi-

dize in the nascent state and so form gas instead of depositing.

It has been stated that the supplies of finely-divided air are unbalanced, which of course means that they are presented under different conditions at the respective sides of the wick. Above the interspace the mixture of air and vapor may be burned to produce a single flame, or, if desired, it may be burned to produce several flames. However, the lowest flame is in action always remote from and out of contact with the wick. The vapor in and above the interspace may be variously treated, as by the addition of further supplies of air to fit it for final combustion.

In the drawings, *a* and *a'* represent wick-tubes.

e and *e'* represent what may be termed "extensions" of the wick-tubes, and they constitute one type of means or screens for introducing unbalanced supplies of finely-divided air into the interspace *c*. To this end they may be made foraminous, and the openings in one of them may be different from the openings in the other. As shown, the inner tube *e* is obstructed at its top and the outer tube *e'* is proportioned to afford a space between its lower portion and the wick. The introduction of air to the interspace—or, in other words, beneath the flame—may be further modified by means of suitable cones or deflectors or combinations thereof—as, for example, *f* and air-conveyers, as *f'*, may be used.

g indicates a chimney, and it will be understood that the wick-tube when hollow is provided with a center draft or air-inlet and with means for moving the wick to start and adjust the flame, and that air is admitted to the base of the chimney. It is the heat of the flame which burns above the interspace *c* that serves to vaporize oil from the wick. The conditions which produce the introduction of unbalanced supplies of finely-divided air may be brought about by almost endless variations in the relations of the screens *e* and *e'*. For example, they may be constructed with belts of different-sized openings or dimensions, or they may be simply provided with belts which have no openings at all, or, again, they may simply be provided with openings of different characters, as has been described.

It will be obvious to those skilled in the art to which the invention relates that modifications may be made in detail without departing from the spirit thereof. Hence I do not limit myself to the precise construction and arrange-

ment of parts hereinabove set forth and illustrated in the accompanying drawings; but,

Having thus described the nature and objects of the invention, what I claim as new, and 5 desire to secure by Letters Patent, is—

1. The method of burning oil from a wick which consists in maintaining an interspace between the flame and the wick by feeding quantitatively unbalanced supplies of finely-divided air between the wick and flame, substantially as described.

2. The method of burning oil from a wick which consists in maintaining an interspace of vapor between the flame and the wick by 15 feeding quantitatively unbalanced supplies of finely-divided air between the wick and flame, and feeding a supply of additional air to said vapor above said unbalanced supplies of finely-divided air, substantially as described.

20 3. The method of burning oil from a wick which consists in establishing at the top of the wick and between it and flame conditions adverse to combustion by the introduction of quantitatively unbalanced supplies of air, substantially as described.

4. The method of burning oil from a wick which consists in establishing between the wick and flame conditions adverse to combustion by the introduction of quantitatively unbalanced supplies of air, and establishing 30 above said region adverse to combustion conditions favorable to combustion, substantially as described.

5. The method of burning oil from a wick which consists in maintaining an interspace 35 between the wick and the flame by means of quantitatively unbalanced supplies of finely-divided air, and in subjecting both the exposed lateral surfaces of the wick to the action of said finely-divided air thereby preventing 40 combustion and the deposition of carbon and pyroligneous products on such surfaces, substantially as described.

In testimony whereof I have hereunto signed my name.

JOHN FREDERICK W. JOST.
